UNITED STATES PATENT OFFICE.

OTIS R. RUST, OF CLEVELAND, OHIO.

BELT-BUCKLE.

1,263,605.

Specification of Letters Patent. Patented Apr. 23, 1918.

Application filed June 14, 1915. Serial No. 33,855.

To all whom it may concern:

Be it known that I, OTIS R. RUST, a citizen of the United States, residing at Cleveland, in the county of Cuyahoga and State 5 of Ohio, have invented a certain new and useful Improvement in Belt-Buckles, of which the following is a full, clear, and exact description.

This invention relates to wearing apparel, the invention being more particularly directed toward a belt worn around the 10 waist.

The object of the invention is to provide a belt and buckle in which the row of unsightly eyelets which commonly appear in 15 all belts for purposes of adjusting the length of the belt are largely done away with, and to provide a buckle which hides the eyelets by which the belt is made adjustable.

Generally speaking, the invention comprises the elements and combinations thereof set forth in the accompanying claims.

Reference should be had to the accompanying drawings forming a part of this 25 specification, in which Figure 1 is a front elevation of a portion of the belt; Fig. 2 is a rear elevation of a portion of the belt; Fig. 3 is a transverse section through a portion of the belt and buckle; Fig. 4 is a perspective view showing the relation of the ends 30 of the belt to the buckle; and Fig. 5 is a transverse section through the buckle.

One end of the belt is represented at 1 and the opposite end is represented at 2. 35 The end of the belt 1 is a plain unpunctured strap, while the end 2 of the belt is provided with two eyelets represented at 3 and 4.

The buckle comprises a front plate 5 which may be ornamental to any degree desired, and a rear plate 6 which is hinged to 40 the front plate, as indicated at 7. The rear plate 6 is cut away to provide an open space, as indicated at 8. The part 5 of the buckle 45 is provided with inwardly extending flanges 5^a; also the part 6 of the belt is provided with inwardly extending flanges 6^a. These flanges overlap and form a casing when the parts of the buckle are together. The ends 50 of the flanges 5^a and 6^a are provided the one with a depression and the other with an extension, which engage each other for the purpose of holding the parts of the belt 5 and 6 together when they are in closed 55 position.

The plate or the part 6 of the belt is provided with an upwardly extending pin 9, which is adapted to coöperate with either one of the eyelets 3 or 4, according to the adjusted position of the belt. At one end 60 of the buckle is a device for holding an end of the belt in such a manner that it may be readily released. This device comprises a lever 11 mounted upon the pintle 10, which forms the hinge by which the parts 65 5 and 6 are connected. This lever has an extending portion 12 which is provided with teeth adapted to engage in the material of which the belt is made. The end of lever 11 extends toward the front plate 5 of the 70 belt, as will be clearly indicated in Fig. 3. Therefore, when the eyelet 4 is in engagement with the post 9 the end of the belt adjacent the eyelet 3 will extend along the lever 11 and through the space 8. 75

The two eyelets 3 and 4 are spaced apart a distance calculated to give an adjustment of approximately an inch, but it will be observed that even when the eyelet 3 is in engagement with the post 9 the eyelet 4 does 80 not extend without the part 5 of the belt, so that it is not visible. When, on the other hand, the eyelet 4 is in engagement with the post 9, the belt extends out through the opening 8 in the part 6 of the belt, so that 85 under these circumstances the eyelets are not visible.

The length of the belt may be generally adjusted by releasing the end 1 from the lever 11 which holds it and cutting the belt 90 until it is approximately the right length. Then the closer adjustment of the belt will be taken care of by the eyelets 3 and 4.

Experience has demonstrated that a belt requires only a limited amount of adjustment which would be amply afforded by the adjustment permissible by eyelets 3 and 4. 95

The adaptability of the belt herein shown makes it possible to manufacture and carry in stock belts of a limited number of lengths, 100 because the strap of the belt may be shortened as required.

And further, while securing the results just enumerated, the appearance of the front of the belt is greatly improved by doing 105 away with the long row of eyelets at present used, and also the loops which are intended to receive the end of the belt.

Having described my invention, I claim:

1. A belt buckle having a back member 110

and a cover member, means carried by one of said members for holding the end of a belt, means carried by one of said members for engaging an eyelet of a belt, the said back member being provided with an opening adapted to receive the free end of a belt.

2. A belt buckle having a back member and a cover member which are pivotally secured together, the said members co-operating to form a box-like structure, means carried by one of said members adapted to receive and retain an end of a belt, a pin carried by one of said members and adapted to receive an eyelet of a belt, the back member 10 of the buckle being provided with an opening adapted to receive the free end of the belt which lies beyond the said post.

3. A belt buckle having a back member and a cover member, means carried by one 20 of said members for receiving and retaining the end of a belt, said means lying between the back member and the cover member, a pin carried by one of said members adapted to receive an eyelet of a belt, said post also

lying between the back member and the 25 cover member, the back member being provided with an opening, which opening lies adjacent the means for holding one end of the belt, the said opening being adapted to receive the free end of the belt.

4. A belt buckle comprising a back member and a cover member, a clamping device carried by the cover member, said clamping device adapted to receive the end of a belt, an opening formed in the back member, said 30 opening being in position opposite to the said clamp, a member adapted to engage with an eyelet of a belt, said member being carried by the back member of the belt and positioned so as to be well removed from 40 the end of the back member.

In testimony whereof, I hereunto affix my signature in the presence of two witnesses.

OTIS R. RUST.
